Patented July 17, 1928.

1,677,741

UNITED STATES PATENT OFFICE.

WILLIAM T. WHITAKER, OF ELKINS PARK, PENNSYLVANIA
HOLDER FOR MOPS.

Application filed September 22, 1926. Serial No. 137,148.

My invention relates to an improvement in holders for mops and more particularly to holders adapted for use in connection with mops of the type used for dusting and 5 polishing.

Heretofore various types of mop and duster holders have been produced, but in the main such holders have been found to be relatively unsatisfactory where it is desired to 10 use the mop for general dusting and polishing, especially where it is desired to have the mop effective in odd corners, as for example, under radiators.

Now in accordance with my invention, I 15 provide a mop holder so constructed for attachment to a mop as to permit the mop to be made effective in a variety of ways for dusting and polishing and to enable its use at various angles relative to the handle.

Having now indicated, in a general way, 20 the nature and purpose of my invention, I will proceed to a detailed description thereof with reference to the accompanying drawings in which there is illustrated a preferred 25 embodiment and in which:—

Fig. 1 is a perspective view of a mop equipped with a handle embodying my invention.

Fig. 2 is an elevation of the lower end of 30 the handle and attaching means embodying my invention.

Fig. 3 is a detailed view of a modification of one of the fastening means.

Figs. 4 and 5 are detailed views of means 35 for attaching the handle to a mop.

Fig. 6 is a detailed view of a modification.

Referring to the drawings A indicates a 40 dusting or polishing mop having a loop B on its upper surface. The mop A may be, for example, constructed in accordance with the disclosure of the application for United States patent of William D. Whitaker, filed June 21, 1926, Serial No. 117,290.

C indicates a handle which may be made 45 of any desirable material, as wood, and of any desirable length. The handle C is provided in its lower end with a slot D and adjacent its lower end with aligning holes E extending at right angles to and opening into slot D.

F indicates a connector for securing the 50 handle C to the mop A. The connector is formed, preferably, from relatively heavy wire bent upon itself to form a loop f and having its end portions f' extending in opposite directions and slightly out of line, one

of the end portions being of greater length than the other as illustrated in Figure 2. The end of the longer end portion f' of the connector may be protected by a ball G, or 60 bent around upon itself as at I. The end portions f' of the connector are adapted to be extended into the loop B of the mop, from opposite ends to secure the connector to the mop, and the loop f is adapted to be inserted 65 in the slot D in handle C, as shown in Figure 1.

The loop f of the connector is retained in handle C by means of a clasp H, preferably formed from heavy wire, bent to form a 70 curved end portion h extending throughout slightly more than 180° and the radius of which is about that of the handle, and a straight end portion h' extending at an angle to the intermediate portion of the clasp. 75 The end portion h' of the clasp is adapted to be passed through the holes E in the handle C and through loop f of the connector securing the connector to the handle. 80 Since the end portion h' is at an angle to the intermediate portion of the clasp, the intermediate portion extends at an angle to the handle when the portion h' is entered in holes E. The clasp is secured to the handle by engaging its curved end portion h about the handle, which causes the intermediate portion of the clasp to be sprung in and put under tension, which tends to prevent withdrawal of end portion h' from holes E. 85 The curved portion h, since it extends more than 180°, extends more than half way around the handle and will not disengage itself.

Having now fully described my invention, what I claim and desire to protect by Letters Patent is:—

A holder for a mop comprising a handle 90 provided with a slot extending inwardly from one end thereof, a mop holding member extending within the slot, and a pin extending through the handle and across the slot and forming a pivotal mounting for the member, said pin being provided with a clip at one end of the pin and embracing the handle, said clip extending about the handle 95 from its junction with the pin beyond the free end of the pin.

In testimony of which invention, I have hereunto set my hand at Philadelphia, Penna., on this 14th day of September, 1926.

WILLIAM T. WHITAKER.
